2 SHEETS—SHEET 2.

UNITED STATES PATENT OFFICE.

PETER HAMER, OF CADDO, OKLAHOMA.

GATE FOR RAILWAY-CROSSINGS.

No. 917,939.

Specification of Letters Patent.

Patented April 13, 1909.

Application filed December 31, 1907. Serial No. 408,715.

To all whom it may concern:

Be it known that I, PETER HAMER, citizen of the United States, residing at Caddo, in the county of Bryan and State of Oklahoma, 5 have invented certain new and useful Improvements in Gates for Railway-Crossings, of which the following is a specification.

The present invention provides novel means for safe guarding a roadway intersected by a railroad so that persons may be 10 warned in ample time of the approach of a train so as to avoid a casualty, said warning being made more effective by interposing a barrier to prevent the crossing of the railway 15 track, said safety means being automatically actuated by the moving train, being set on the approach of the train and restored to normal condition after the train has passed the crossing.

20 For a full understanding of the invention and the merits thereof reference is to be had to the following description and accompanying drawings.

25 While the invention may be adapted to different forms and conditions by changes in the structure and minor details without departing from the spirit or essential features thereof, still the preferred embodiment is shown in the accompanying drawings, in 30 which:

Figure 1 is a perspective view of a railway crossing provided with safety appliances embodying the invention, parts being broken away to show more clearly the relative arrangement and the construction of certain 35 elements. Fig. 2 is a side view of the safety devices, parts being broken away and showing the arrangement of the elements when the gates are lowered. Fig. 3 is a transverse 40 section on the line $x-x$ of Fig. 2. Fig. 4 is a detail perspective view of an operating wheel, as seen from the inner side. Fig. 5 is a perspective view of a lantern and support showing the position of the same when the gates 45 are elevated. Fig. 6 is a perspective view of the parts shown in Fig. 5, illustrating their arrangement when the gates are lowered. Fig. 7 is an elevation of one of the operating 50 wheels 7 as seen from the inner side, showing the normal position of the parts when the gate is open. Fig. 8 is a view of the parts shown in Fig. 7, illustrating the relation of the parts when the gate is closed. Fig. 9 is a 55 section on the line $y-y$ of Fig. 3, showing top shaft and coöperating spring.

Corresponding and like parts are referred

to in the following description and indicated in all the views of the drawings by the same reference characters.

The invention may be either applied to a 60 single or a double track and may embody one or more gates.

As illustrated in Fig. 1 the invention is shown in connection with a roadway intersected by double tracks, a pair of gates being 65 arranged at the outer side of each of said tracks.

At any safe distance from the crossing at each side thereof are located two shafts 1 and 2, the same lying one above the other and extending transversely of the tracks and mounted in suitable bearings to receive an oscillatory movement. Each shaft 1 is provided with a trip 3 normally extended vertically to be engaged by a part of the train so 75 as to be depressed. A cross bar 4 fast to each shaft 1 and extended from opposite sides thereof, is normally pressed upon by means of a flat spring 5, which is secured to a tie or other convenient portion of the road- 80 bed. The shafts 1 and 2 are adapted to be turned in either direction and the shafts 1, when relieved of the restraining influence of the train, are returned to normal position by means of the respective coöperating springs 85 5. An arm 6 projects vertically from each shaft 1 and is adapted to actuate the adjacent operating wheel 7. It is to be understood that each shaft 1 is provided with a trip 3 and an arm 6 for each track. 90

Each shaft 2 is provided at opposite ends with operating wheels 7 fast thereto. The operating wheels 7 are grooved in their outer edges and each is provided on its inner side with an approximately U-shaped spring 10 95 fast at its closed end to the wheel, the arms being free and arranged upon opposite sides of the adjacent arm 6. When the shaft 1 is turned in one direction, its arms 6 engage with members of the adjacent U-shaped 100 springs 10 to effect a corresponding turning of the shaft 2. The space between the members of the U-shaped springs 10 is such as to permit the shaft 1 to return to normal position after actuating the operating wheel 7 105 without moving said operating wheel backward or to its normal position. Hence when the shaft 1 is tripped upon the approach of a train and the gates are lowered, they remain in such lowered position until the train has cleared the crossing and actuates the trip shaft upon the far side. By having the

members of the parts 10 resilient, shock is avoided when the shaft 1 is tripped to actuate the operating wheel, the sudden impact of the arm 6 on a member of the part 10 being compensated for by the spring action of said member.

A second operating wheel 11 is provided for each gate and is preferably located opposite the same and is connected with the first 10 mentioned operating wheel 7 on the same side by cables or chains 12 and 13, said connections 12 and 13 being attached to the respective operating wheels 7 and 11 in such a manner as to cause the wheels 11 to move in 15 opposite directions at the same time so that when one connection 12 is moving to the right, the other connection 13 is at the same time moving to the left. Pairs of guide pulleys 14 are located near the operating wheels 20 7 and 11 and give proper direction to the flexible connections, 12 and 13. The portions of the connections 12 and 13 between opposite pairs of guide pulleys 14 are housed to protect them from the weather, dirt, 25 stones or other matter which would tend to interfere materially with their free operation. The housing 15 consists of a pipe, the end portions of which are split and forked to receive the pairs of guide pulleys 14. Cables, 30 chains or like flexible connections 16 and 17 are secured at opposite ends to the operating wheels 11 so as to transmit motion from one to the other. Corresponding ends of the connections 16 and 17 are attached to opposite 35 site portions of the respective operating wheels 11 to cause them to move in opposite directions. Pairs of guide pulleys 18 direct the connections 16 and 17 near the operating wheels 11 and are supported by forked ends 40 of a pipe 19 forming a housing for connections 16 and 17. The pipe 19, besides protecting the connections 16 and 17 from the elements and from accumulations, such as dirt and stones, also prevents injury to the 45 parts 16 and 17 from passing vehicles.

Each gate 20 consists of a bar secured to a shaft 21 mounted in bearings of a post or support 22. The gate is counterbalanced in the accustomed way to insure free movement thereof so that the operating force 50 may overcome the inertia and friction of the parts. A cross bar 23 is fast to the outer end of each shaft 21 and its arms are connected to opposite sides of the adjacent 55 operating wheel 11 by means of chains or cables 24 and 25. Springs 26 of the contractile type are interposed in the length of each connection 24 and 25 so as to neutralize shock that may result from the quick movement of the operating wheel when actuated 60 by the moving train. The gates open upward and close downward by a pivotal movement.

In operation, a train approaching the 65 crossing from the right depresses the right

hand trip and actuates the right hand operating wheel 7, and through the flexible connections lowers the gates and turns the left hand operating wheel 7 toward the crossing. As the train actuates the left hand trip on 70 the far side after passing the crossing, the gates are elevated and the right hand operating wheel 7 is returned to normal position to be again actuated by the next train approaching the crossing from the right. The 75 same operation takes place when a train approaches the crossing from the left, the gates being lowered upon the train actuating the left hand operating lever 7 and again returned to normal position after the train has 80 cleared the crossing and actuates the right hand operating wheel 7.

In order that the position of the gates may be seen at night and their position made known, a lantern 27 is carried by each, and 85 for this purpose a rod 28 forming a support for the lantern, is attached at one end to the gate and its opposite end is provided with two loops 29 and 30 arranged at right angles to each other and having adjacent portions 90 connected by a part common to each. The loop 29 is at the extremity of the rod 28 and occupies a position at right angles to the tracks. The loop 30 is at the side of the rod 28 and is arranged lengthwise of the tracks. 95 When the gates are raised, the lantern 27 is suspended from the terminal loop 29 and indicates safety along the road intersected by the railway tracks. When the gates are lowered, the lantern 27 is suspended from 100 the side loop 30 and indicates danger along the roadway. The lantern automatically moves from the terminal loop 29 to the side loop 30 and vice versa, and in such movement is given a one-quarter turn, thereby 105 showing safety when the gates are raised and danger when the gates are lowered. When the gates are raised, the terminal loops 29 occupy the lowermost position, hence the lantern handle hangs suspended from such 110 loop. When the gates are lowered, the loops 30 occupy a lower position than the terminal loops 29 and lantern hanging suspended from said loops 30 indicate danger. The engaging part common to the two loops 29 and 115 30 is such as to admit of the lantern automatically moving from one loop to the other as the gate is either raised or lowered.

Having thus described the invention, what is claimed as new is:

1. In means for protecting a railway crossing, the combination of a gate, an operating wheel, spaced members applied to a side of the operating wheel, connecting means between the operating wheel and gate embodying flexible connections, guide means for said flexible connections, a trip shaft, means for holding the trip shaft in a normal position, and an arm rigid with the trip shaft and arranged to operate between the spaced 125 130

members of the said operating wheel to move the latter in one direction to operate the gate and to permit the return of said arm and trip shaft to normal position without moving 5 the operating wheel or gate.

2. In means for protecting a railway crossing, the combination of a gate, an operating wheel, connecting means between the operating wheel and gate, a trip shaft provided 10 with an arm, and spaced spring members secured to said operating wheel and arranged upon opposite sides of the arm of the trip shaft to receive the impact thereof and adapted to neutralize the shock resulting 15 from said impact.

3. In means for protecting a railway crossing, the combination of a gate, an operating wheel, connecting means between the operating wheel and gate, a trip shaft provided 20 with an arm, and a U-shaped spring secured to a side of the operating wheel and having its members free and arranged upon opposite sides of the arm of the trip shaft to receive and neutralize the impact thereof.

25 4. In safety means for railway crossings, the combination of a gate, an operating wheel, connecting means between the operating wheel and gate, spaced members attached to said operating wheel, a trip shaft 30 having an arm arranged to operate between

the said spaced members and provided with a cross bar, and a spring normally exerting a pressure on the arms of said cross bar to maintain and return the trip shaft to normal position.

35

5. In a safety means of the character specified, the combination of a gate, an operating wheel 11 having connection with the gate, operating wheels 7 arranged upon opposite sides of the operating wheel 11, 40 spaced members applied to a side of each of the operating wheels 7, flexible connections between the operating wheel 7 and 11 to effect simultaneous movement of the operating wheels 7 in opposite directions, trip 45 shafts coöoperating with the operating wheel 7, and arms rigid with the respective trip shafts and arranged to operate between the spaced members of the operating wheel 7 to move the latter in one direction, and 50 admitting of the arm returning to normal position without imparting movement to the said operating wheel and gate.

In testimony whereof I affix my signature in presence of two witnesses.
